His Attorney

UNITED STATES PATENT OFFICE.

JOE PICKLES, OF WINNIPEG, MANITOBA, CANADA.

PROTECTOR FOR CHILDREN.

1,264,971.

Specification of Letters Patent.

Patented May 7, 1918.

Application filed February 19, 1917. Serial No. 149,543.

To all whom it may concern:

Be it known that I, JOE PICKLES, a citizen of the Dominion of Canada, residing at the city of Winnipeg, in the Province of Manitoba, in the Dominion of Canada, have invented certain new and useful Improvements in Protectors for Children, of which the following is a specification.

This invention relates to means for protecting a child from the inclemency of the weather, and the object of the invention is to provide a device of this class in which the child may be placed when it is being drawn in a sleigh or carriage, or even when it is being carried by hand, and by which its hands and arms as well as all other parts of the body including the head when necessary, will be fully protected in the severest weather.

Another object of the invention is to so shape the protector that it will conform to the natural sitting posture of the child when in it, and without the bunching and straining of the material necessarily accompanying the changing of the shape of protectors of different construction.

With these and certain other objects in view which will appear as the description proceeds, the invention consists in the novel combination and arrangement of parts fully described in the following specification then more particularly pointed out in the appended claims, reference also being had to the accompanying drawings forming part hereof, in which similar characters of reference refer to similar parts throughout the different views and in which—

Figure 1 shows a child clothed with the device and seated in a sleigh.

Fig. 2 is a perspective view of one of the devices with the lacing removed to show the chest and shoulder protectors separate, the form differing slightly from that shown in Fig. 1, in that the side flaps are longer and laced farther down.

Fig. 3 is a section between the lines 3—3 in Fig. 2.

Fig. 4 is one of the side pieces, these being used in duplicate.

Fig. 5 is the back piece to which the rear ends of the sides are joined.

Fig. 6 is the bottom piece or sole, and

Fig. 7 is the top piece.

The device may be made from a variety of fabrics or even fur, but the intention in the drawings is to show it as formed from the outer and inner sheets of fabric 2 and

3 having a sheet of cotton batting 4 therebetween, the whole being quilted on the dotted lines 5.

The envelop as a whole resembles a moccasin of very large size but certain points in the construction differentiate it therefrom and specially adapt it to the purpose for which it is intended. The cutting of the various parts of which the device is built up is of course subject to a wide variation but I prefer to shape the sides 6 as shown in Fig. 4, these being in duplicate and having forwardly offset portions 7, provided with eyelets 8, to receive a cord 9, by which the portions 7 are laced together when the article is in use.

The rear ends 10 of the sides 6 are joined to the edges 11 of the back 12, the upper portion of the edges of the back and sides being preferably slightly beveled back as at 13 and 14 respectively so that the finished article may conform loosely to the shape and shoulders of the child.

The bottom 15 (Fig. 6) corresponding to the sole of a shoe, is preferably made wider at the rear end 16 than at the front 17 and it is seamed to the lower edges of the sides 6 and back 12.

The front 18 is preferably a strip such as shown in Fig. 7, having its forward edge 19 joined to the front edge 17 of the bottom then brought up over to form the toe 20 of the device, the edges 21 of the top being joined to those 22 of the sides up the points 23 thereon, the remainder 24 of the top forming a chest protector for the child, over which the offset portions 7 of the sides are laced.

From the foregoing description it will be understood that when it is desired to make use of the envelop or protector the child is merely seated therein, the rear end or heel 25 being of a width to accommodate the hips of the child while the toe is preferably square as shown and of ample size to receive both feet in vertical position. The front is then laced up by means of the cord 9 thus inclosing the child up to the neck and preventing him from getting his arms out into the cold. Due to the shaping of the sides and back and also the angle at which the forward edges 26 of the parts 7 are cut the upper part of the device draws well in around the neck and the child is fully protected.

27 indicates by heavy dotted lines in Fig.

2, and full lines in Fig. 1, a portion of the side being broken away to show the same, a removable absorbent pad having a water proof bottom, positioned as shown in the rear of the device, the purpose of which is self evident.

The front or top 18 it will be noted is preferably bifurcated at the top to provide a circular opening 28 this fitting around the 10 neck of the child when the ends 29 are carried around to the back, the center of the back piece 12 being provided with a hook 30 and the ends 29 with loops or eyes 31 to be secured on the said hook, to maintain the ends in position. As an alternative to the shaping of the top 18 as described, this may be cut off on the dotted lines 32 in Fig. 7.

As previously mentioned the article may 20 be made of fur throughout or it may be fur lined, or it may be made of rubber or leather, in fact the material of which it may be made is without limit, and the various parts may be cut on different lines from those herein 25 shown without departing from the spirit of the invention.

Having thus fully described my said invention what I claim is,—

1. A garment shaped to provide a lower 30 closed portion and an upper open portion at right angles to the closed portion and merging thereinto, the top of the closed portion being extended to form a tongue adapted to turn up in front of the open portion, and 35 the sides of the open portion being shaped to form flaps adapted to be disengageably connected across the tongue.

2. A garment shaped to provide an envelop closed for a portion of its length and 40 having the sides and back of the remainder extended to form an open portion higher than the closed portion at right angles thereto and merging thereinto, the top of the closed portion being extended to form a 45 tongue in front of the open portion, and the sides of the open portion forming flaps adapted to be lace connected across the tongue.

3. A garment having a lower closed portion and an upper open portion at right angles to the closed portion and merging there-

into, the said portions being formed from a bottom piece extending the length of both portions, and sides, rear end and top pieces joined together, the side pieces being shaped 55 to provide a low portion and a high portion at right angles to the low portion seamed to the rear end piece on upwardly converging lines, the upper piece closing the top of the low portion and extending therebeyond to 60 form a tongue in front of the open portion, and the sides of the open portion forming flaps adapted to be laced across the tongue.

4. A garment having an upper open portion and a lower closed portion extending 65 laterally from the open portion, the said portions being formed with an oblong bottom piece extending the length of both portions and sides and a rear end piece seamed together and to the bottom piece around 70 three sides thereof, the said side pieces being shaped to provide a low portion and a high portion adjacent the rear end piece, and flaps on the forward edges of the high portions, a top piece seamed to the front of 75 the bottom piece, thence passing up over and seamed to the front and upper edges of the side pieces the length of their lower portions and extending therebeyond to form a tongue adapted to turn up and form the 80 front of the open portion, the flaps on the sides being adapted to overlap the tongue and to be disengageably connected thereacross.

5. A garment formed from a plurality of 85 parts joined together, the said parts comprising an oblong bottom piece, a rear end piece and sides joined to the end piece on upwardly converging lines, the sides being shaped to provide a low portion and a high 90 portion at right angles to the low portion adjacent the rear end piece and having forwardly extending flaps, a top seamed to the upper edges of the low portion of the sides and extending therebeyond to form a tongue 95 having its extremity bifurcated, means on the rear end piece and the separated end of the tongue whereby they may be releasably connected, and means to releasably connect the flaps on the sides of the open portion 100 across the tongue.

JOE PICKLES.
